UNITED STATES PATENT OFFICE.

ERIC ZETTERQUIST, OF ESSINGTON, PENNSYLVANIA, ASSIGNOR TO WESTINGHOUSE ELECTRIC AND MANUFACTURING COMPANY, A CORPORATION OF PENNSYLVANIA.

TURBINE BLADING.

Application filed September 13, 1922. Serial No. 588,039.

To all whom it may concern:

Be it known that I, ERIC ZETTERQUIST, a citizen of the United States, and a resident of Essington, in the county of Delaware and State of Pennsylvania, have invented a new and useful Improvement in Turbine Blading, of which the following is a specification.

My invention relates to turbines, more particularly to the low-pressure or exhaust blading thereof, and it has for its object to provide apparatus of the character designated which shall be capable of efficiently abstracting energy from large volumes of low-pressure motive fluid, whereby single-unit turbines of large capacity may be constructed.

Apparatus made in accordance with my invention is illustrated in the accompanying drawings, forming a part of this application, in which: Fig. 1 is a longitudinal sectional view of a turbine showing my improved low-pressure blading applied thereto; Fig. 2 is a fragmentary perspective view showing a portion of my improved blading; Fig. 3 is a sectional view of a single low-pressure blade taken along the line III—III of Fig. 1; Fig. 4 is a detail sectional view showing a modified form of my low-pressure blading; Fig. 5 is a sectional view taken along the line V—V of Fig. 4; and Fig. 6 is a detail view showing a further modified form of my improved blading.

In the application of Henry F. Schmidt, Serial No. 482,768, filed July 6, 1921 and in the application of Alexander T. Kasley, Serial No. 486,517, filed July 21, 1921, continued as Serial No. 521,872, filed December 12, 1921, both of which applications are assigned to the Westinghouse Electric & Manufacturing Company, there are disclosed forms of low-pressure or exhaust turbine blades which are capable of handling large volumes of low-pressure motive fluid efficiently. It is characteristic of the improved moving blades shown in these applications that motive fluid is received axially and discharged radially or radially and axially. In accordance with my invention, blading of this general type is provided with energy-absorbing portions, which are inclined with respect to the axis of rotation so that motive fluid may be discharged peripherally without being turned as far as it is necessary with the radially-discharging type,

with the result that a saving in energy is effected and more energy is available for conversion into useful work.

Referring to the accompanying drawings for a more detailed description of my invention, I show a turbine at 10 comprising a rotor 11 and a casing or cylinder 12 provided with energy-absorbing elements, at 13 and 14, and of a conventional type, followed by my improved low-pressure stage 15.

The low-pressure stage, at 15, consists of a row of guide blades 16, carried by the casing or cylinder 12, and a row of wide blade structures 17, carried by the rotor 11.

The wide blade structures 17 each include a series of sections 18 having inner plane portions and outer curved or spoon-outline, energy-absorbing portions 19, which are inclined to the turbine axis to provide conical paths of discharge for the motive fluid so that the latter may be discharged peripherally with a diversion from an axial path of flow which is materially less than 90°. Plane sections 20 are interposed between the sections 18 and they are provided with shroud elements 21, which contact to form enclosed motive fluid passages between adjacent rows of sections 18. The shroud elements 21 are preferably inclined oppositely to the energy-absorbing portions 19 so that, when the blading is assembled, the tips present a serrated appearance with like sides of the serrations provided with energy-absorbing portions 19 and the other like sides provided with shrouds.

In Fig. 1, the last section 18 is followed by a section 22, which discharges both axially and peripherally. See Fig. 3. With this arrangement of blading, motive fluid is received axially and it is discharged peripherally by the energy-absorbing portions 19 and axially by the axially-discharging portions of the sections 22.

In Figs. 4 and 5, I show a form of my low-pressure blading in which the entire discharge is peripheral. The axially-discharging sections 22 are omitted and only the energy-absorbing portions 19 of the serrations are provided. However, in order to direct the motive fluid outwardly, curved deflectors 23 are arranged between the blade structures 17.

In Fig. 6, I show a further modified form of my low-pressure turbine stage in which

- the moving blade structure thereof is made up of a plurality of sections 25 having wedge-shaped tips 26. Similar inclined sides 27 of the wedge-shaped tips are 5 shrouded by stationary elements 28 and 29. The portions 28 are supported in any suitable manner by the turbine cylinder casing and the portion 29 constitutes a part of said casing or cylinder. The other sides of the 10 wedge-shaped tips 26 are provided with curved energy-absorbing portions 30 of the spoon-outline type, already referred to, and the last section 25 of each blade structure is provided with an axially-discharging energy-absorbing portion 31.

From the foregoing, the operation of apparatus made in accordance with my invention will be apparent. Motive fluid, such as steam, is expanded and energy is abstracted 20 in the sections 13 and 14 in the usual way; and, after discharge from the latter section, the motive fluid then enters the low-pressure stage 15 for further expansion and energy abstraction. The peripheral discharge of motive fluid permits of the provision of adequate discharge area with the preservation of highly efficient discharge angles without exceeding safe centrifugal stresses in the material of the blades since 25 the extent of discharge area is determined by the blade width instead of the blade height, as is ordinarily the case. As motive fluid in my case is diverted materially less than 90°, less energy is lost in turning the stream 30 outwardly and more energy is available for doing useful work than would be the case if the diversion was substantially 90°.

While I have shown my invention in but three forms, it will be obvious to those skilled in the art that it is not so limited, but is susceptible of various other changes and modifications, without departing from the spirit thereof, and I desire, therefore, that only such limitations shall be placed 45 thereupon as are imposed by the prior art or as are specifically set forth in the appended claims.

What I claim is:

1. A turbine blade comprising a plurality of inclined energy-absorbing portions at the tip separated by shrouding and disposed laterally with respect to each other. 50
2. In a turbine, a row of blades having a series of inclined energy-absorbing portions at the tips defining a series of conical discharge paths for steam. 55
3. In a turbine, a row of moving blade structures each of which comprises a series of outer curved energy-absorbing portions separated by shroud portions. 60
4. In a turbine, a row of moving blade structures each of which comprises a plurality of inclined, tip-discharging, energy-absorbing portions followed by an axially-discharging energy-absorbing portion. 65

5. In a turbine, a row of blades having serrations at the tips with like sides of the serrations provided with curved energy-absorbing portions. 70

6. In a turbine, a row of blades having serrations at the tips with like sides of the serrations provided with curved energy-absorbing portions and with the other sides of the serrations being shrouded. 75

7. In a turbine, a row of blades having laterally-disposed energy-absorbing portions and being serrated at the tips with like sides of the serrations provided with energy-absorbing portions. 80

8. In a turbine, a row of moving blade structures each of which comprises a plurality of juxtaposed sections with alternate sections having curved energy-absorbing portions at the tips. 85

9. In a turbine, a row of moving blade structures each of which comprises a plurality of juxtaposed sections with alternate sections having the tips inclined with respect to the turbine axis and having curved energy-absorbing portions at the tips. 90

10. In a turbine, a row of moving blade structures each of which comprises a plurality of juxtaposed sections with alternate sections having curved energy-absorbing portions at the tips and the interposed sections being shrouded. 95

11. In a turbine, a row of moving blade structures each of which comprises a plurality of juxtaposed sections with alternate sections having the tips provided with curved energy-absorbing portions and inclined with respect to the axis of rotation and with the interposed sections having shrouds at the tips inclined in the opposite direction to the axis of rotation. 100

12. In a turbine, a belt of exhaust blades mounted on a rotor body and each comprising a flat body portion lying in substantially a radial plane and an exhausting tip of spoon-outline having its outer surface lying at an acute angle with the rotor axis. 105

13. In a turbine, a belt of exhaust blades mounted on the rotor body, adapted to receive motive fluid in a direction parallel to the rotor axis and to exhaust said fluid in a frusto-conical surface. 115

14. In a turbine, a series of belts of exhaust blades mounted on the rotor body, each adapted to receive motive fluid in a direction parallel to the rotor axis and to exhaust said fluid in a frusto-conical surface, and a series of intervening belts of fluid retaining members, interposed therebetween, respectively and of opposed frusto-conical overall configuration. 120

15. In a turbine, a series of belts of exhaust blades mounted on the rotor body, each blade comprising a flat body portion disposed substantially parallel to a rotor radial plane and a tip portion of hook cross 130

section, the outer surface of which, if extended, would intersect the rotor axis, whereby an exhausting surface of frusto-conical shape is provided, and an opposed frusto-conical fluid retaining and directing structure interposed between adjacent exhaust blade belts.

16. In a turbine, a series of belts of exhaust blades mounted on the rotor body, 10 each blade comprising a flat body portion disposed substantially parallel to a rotor radial plane and a tip portion of hook cross section, the outer surface of which,

if extended, would intersect the rotor axis, whereby an exhausting surface of frusto-
conical shape is provided, and an opposed
frusto-conical fluid retaining and directing
structure interposed between adjacent ex-
haust blade belts, said structure being com-
posed of a plurality of flat stem members 15
aligning respectively with the flat body por-
tions.

In testimony whereof, I have hereunto
subscribed my name this 7th day of Sep-
tember 1922.

ERIC ZETTERQUIST.
